UNITED STATES PATENT OFFICE.

GEORGE W. MARTIN, OF SOMERVILLE, MASSACHUSETTS, ASSIGNOR OF ONE-HALF TO JOSIAH KNIGHT, OF SAME PLACE.

ELECTRIC SIGNAL AND SEARCH-LIGHT LANTERN.

SPECIFICATION forming part of Letters Patent No. 446,142, dated February 10, 1891.

Application filed February 28, 1890. Serial No. 342,137. (No model.)

To all whom it may concern:

Be it known that I, GEORGE W. MARTIN, a citizen of the United States, residing at Somerville, in the county of Middlesex and State of Massachusetts, have invented certain new and useful Improvements in Electric Signal and Search-Light Lanterns; and I do declare the following to be a full, clear, and exact description of the invention, such as will enable others skilled in the art to which it appertains to make and use the same, reference being had to the accompanying drawings, and to the letters of reference marked thereon, which form a part of this specification.

- 15 Figure 1 is a side elevation, Fig. 2 is a longitudinal section, and Fig. 3 an end elevation, of an electric signal and search-light lantern of my invention. Fig. 4 is a longitudinal section of the same without the exterior casing, and showing one of the ways of connecting the neck of the glass body to the socket supporting the electric lamp. Fig. 5 is a section showing one of the ways of forming the said neck of the glass body and of 20 connecting it to the said socket. Fig. 6 is a section of the neck of the same construction as shown in Fig. 5. Fig. 7 is a section of the spun-metal screw-threaded sleeve, as formed to apply to the neck shown in Figs. 5 and 6. 25 Fig. 8 is an outside view of the socket in which the electric lamp is supported, screw-threaded to connect to said sleeve. Fig. 9 illustrates one way of providing the lamp-socket with an exterior screw-thread to connect to said sleeve. Fig. 10 is a section of a 30 portion of the conical part of the body C on an enlarged scale, and Fig. 11 is a section of the concavo-convex portion of said body on an enlarged scale. Fig. 12 is a side elevation, 35 Fig. 13 an end elevation, and Fig. 14 a longitudinal section, of a lantern, showing one of the ways of connecting the electric lamp to the glass or reflecting body thereof, said lantern also being provided with a chamber in 40 which the conducting wires can be coiled. Fig. 15 is a section of a concavo-convex pane of glass, provided with a lens integral therewith and adapted to be connected to the reflector of the lantern when made of metal. 45 Fig. 16 is a view showing said pane as applied to the reflector with its convex surface

inward. Fig. 17 is a section of a flat pane of glass provided with a lens integral with said pane. Fig. 18 is a longitudinal section of a concave reflecting-glass body, having a closed front and provided with one or more electric lamp-receiving openings in its curved portion. 55

The nature of my invention is defined in the claims hereinafter presented.

In the drawings, A denotes the lantern, consisting of the tapering exterior case B, open at its larger end, the interior body C, also tapering, made of glass or of glass and metal combined, the socket D, connected to the said interior body, and the electric lamp E, which 60 enters into and is supported by said socket.

The construction shown in the first sheet of drawings and the several ways of connecting the socket D to the interior body C relate specially to a lantern for the use of divers in 65 making submarine explorations, working upon sunken vessels, &c., and also for use on vessels for the purpose of signaling, it being adapted for use in places where the lantern is liable to be wet at any time, as it is so 70 constructed that no moisture can get into the light to extinguish it, and in connecting the interior body C, which is usually made of molded glass, to the socket D it is essential 75 that the connection shall be water-tight. 80

In Figs. 2 and 4 the neck of the body C is shown as provided with a screw-thread *a* on its exterior, on which is screwed a spun-metal screw-threaded sleeve F, the flanged end *b* of which bears against a packing between it and 85 the flange *c* on the said body C.

The lamp-socket D in Fig. 2 is screw-threaded on its exterior at *d* to connect with the screw of said sleeve F, said socket being forced against packing at *e* and *f*, as shown. 90

In Fig. 4 the socket is smooth on its exterior and enters the neck of the body C, the flange *g* of the socket and the end *h* of the sleeve being borne against the packings *i* and *j*, respectively, by the setting up of the 95 sleeve F.

In Figs. 5 and 6 the neck of the body C is smooth, and at its junction with said body has an inwardly-projecting flange *k*. A spun-metal screw-threaded lining or sleeve G, having prongs *l* at one end and a flange *m* at the other end and cement applied to its exterior, 100

is introduced into said neck. The shoulder *n* of said lining bears against one side of the flange *k* and the ends of the prongs *l* are turned so as to bear against the other side of said flange and securely confine said lining within the neck. The lamp-socket *D* is screw-threaded on its exterior to connect to the sleeve or lining *G*. (See Figs. 5 and 8.) In some cases I secure a spun-metal screw-threaded sleeve *H* to a lamp-socket *D*, having a smooth exterior (see Fig. 9) and screw said socket, so mounted, into the lining *G*.

In the foregoing description and in the figures of the drawings referred to the body *C* is to be of molded glass, the front *o* thereof being formed or provided either with or without a lens, (see Figs. 2 and 4,) and when provided with a lens the exterior conical surface *p* of said body is coated with a reflecting material *q*, the latter being covered by a protective coating *r*, as in Fig. 10, said reflector throwing the light forward through the said front and the lens; but when said front *o* is unprovided with a lens the concave surface *s* of it may be coated with reflecting material *t*, the latter covered on its exterior with a protective coating *u*, (see Fig. 11,) so as to spread the light upward and outward through the conical portion of the body *C*. In the latter case the glass body may be protected by enveloping it in a wire-netting in place of the exterior casing *B*. A wire-netting *I* is usually applied to the open end of the casing *B* to protect the front *o*, (see Figs. 1 and 2,) and said casing is applied to the body *C*, so that it can be readily detached therefrom, the springs *v* (see Figs. 2 and 3) serving to illustrate one of the ways of connecting the body and the casing.

The casing *B* may also be provided with pockets *w* to receive weights *K* to overcome the buoyancy of the body *C*.

To the casing *B* may be applied a chamber in which the wires are to be coiled to prevent them from becoming tangled, the outer end of the chamber after the wires are placed therein being closed by a cover, the wires being led out of the chamber through an opening therein, as represented in Figs. 12 and 14. The lantern shown in Figs. 12, 13, and 14 is adapted for general use where a powerful light is required and is especially useful in mines, tunnels, holds of vessels, &c., or in any place where it is not liable to become wet. The glass body in this case may be connected to the electric lamp in any suitable manner, it not being necessary that the connection shall be water-tight, and the outer conical surface of said body is coated with a reflecting material, the latter being covered by a protective coating, as shown in Fig. 10.

In making the reflector of the lantern of metal instead of glass, the front end thereof may be closed by a convex, or a concave, or a flat plane of glass provided with a lens, (see Figs. 15, 16, and 17.) *L* representing a portion of a metal reflector; *M*, the glass front or plane, and *N* the lens integral therewith. The convex surface of the front *o* of the glass body *C* when outward, as shown in Fig. 14, may be coated with a reflecting material, the latter covered with a protective coating, as explained, when said body is unprovided with the outer casing *B*. The glass body may be concave, provided with a closed front *w* and one or more openings *r* in its curved portion, as shown in Fig. 18, to receive and support one or more electric lamps, the outer convex surface of said body being coated with a reflecting material, the latter covered with protective coating, as hereinbefore described.

What I claim is—

1. In a lantern, a tapering body *C*, having at its smaller end a flange and screw-threaded neck and at the larger end a concavo-convex front *o*, provided with a lens, all in one piece of glass, combined with a screw-threaded metal sleeve, a socket, and an electric lamp, said socket supporting the lamp and adapted to connect to said sleeve, essentially as shown and set forth, the tapering exterior of the body being covered with a reflecting material, the latter covered with protective coating, as explained.

2. In a lantern, a tapering body *C*, having at its smaller end a flange and screw-threaded neck and at its larger end a concavo-convex front *o*, all in one piece of glass, combined with a screw-threaded metal sleeve, a socket, and an electric lamp, said socket supporting the lamp and adapted to connect to said sleeve, the tapering exterior of the body being covered by a reflecting material, the latter covered by a protective coating, as explained.

3. The lantern consisting of the tapering body *C*, having a flange and neck at its smaller end and a concavo-convex front at its larger end, all of one piece of glass, the metal screw-threaded sleeve connected thereto, the socket connected to the sleeve, the electric lamp secured to the socket, and the exterior casing *B*, applied to the said body essentially as shown.

In testimony whereof I affix my signature in presence of two witnesses.

GEORGE W. MARTIN.
